FIG. 1. 17 / 10

FIG. 2.

JACOB M. DEUTSCH.

By his Attorneys
Bohlke & Leachette

UNITED STATES PATENT OFFICE.

JACOB M. DEUTSCH, OF PHILADELPHIA, PENNSYLVANIA.

BOOKMARK.

Refiling of application Serial No. 189,558, filed May 7, 1927. This application filed June 27, 1928.
Serial No. 288,619.

This application is a refiling of my application U. S. Serial No. 189,558 filed May 7, 1927.

5 This invention relates to a book mark of the kind having a clasp adapted to slip over the top edge of the back of the binding of a book.

10 Heretofore, such clasps have been provided with ribbons or flexible cords adapted to be drawn between the leaves of the book to mark the place. Such flexible place marking devices have the disadvantage that they were not readily discernible when in place between the leaves; do not facilitate the separation of 15 the leaves at the desired place; become readily mussed and crumpled up and soiled and contribute to the tearing of the leaves when an attempt is made to open the book at the place marked thereby.

20 The present invention has for its object the provision of a book mark which shall avoid the disadvantages inherent in previously known book marks and which shall be applicable to books of substantially any size.

25 In accordance with the invention the clasp comprises a flap formed with a downwardly extending tongue cut out therefrom, the flap being adapted to be inserted within the inside of the back binding of a book with the tongue 30 outwardly of the binding so as to grip the binding therebetween. The clasp is also provided, above the tongue, with an elongated transversely extending slot. The slot preferably has an arcuate side upon which is carried 35 a place marking finger or arm. This finger is preferably so designed as to be capable of extending laterally from the clasp to reach the leaves adjacent the covers of the book.

40 The invention also has to do with a book mark which shall be practical from the standpoint of ease and cheapness of manufacture and convenience and durability in use.

45 These and other objects of the invention and the means for their attainment will now be described more fully with reference to the accompanying drawings illustrating one embodiment by which the invention may be realized and in which:

50 Figure 1 is a view in elevation showing a fragmentary portion of a book with the book mark in place.

Figure 2 shows the book mark in perspective.

55 The book mark in accordance with this in-

vention is preferably formed of celluloid or other equivalent pliable but ordinarily relatively inflexible material in order that it may be durable, not subject to deterioration, cheap and readily cleaned, if soiled. It comprises 60 an elongated main portion 5 having a downwardly extending tongue 6 cut out therefrom but joining said portion at its top 7 to form the clasp 5, 6. For convenience, both parts 5 and 6 may be pointed as at 8, 9 so that 65 the clasp may be easily inserted within the binding of a book. As shown in Figure 1, the flap 5 is adapted to be inserted between the back binding 11 of the book and that portion of the leaves 10 of the book where they 70 are sewed together so as to straddle the binding and grip it therebetween.

The top of the clasp is conveniently, but not necessarily, bent over to lie at an angle of approximately 90° to the tongue portion, as 75 at 13, and this inwardly turned portion 13 is formed with an elongated slot 14. The slot 14 is preferably arcuate and may conveniently have the remote side thereof curved as shown at 15 so as to form what is, in 80 effect, a D-ring. The clasp is thus carried on the straight side of the D-ring and a place mark, now to be described, is carried on the curved side 21 of the ring.

The place mark consists of a relatively 85 stiff arm 17 also conveniently formed of celluloid or the equivalent, which arm has a downwardly bent finger 18 at one extremity and is formed at the other end with an enlarged portion 19 having the hole 20 therein. 90 This hole 20 is of a diameter sufficient to receive the curved side 21 of the ring and have full freedom of movement thereon. For convenience in assembly the enlarged part 19 is slotted as at 22 in order to slip the D-ring 95 into the hole 20.

It is obvious that the clasp 5, 6 may slide along the back binding 11 between the covers 24 and 25 and thus be adjustable and capable of use in either a thin book or a thick book, 100 as for instance in either a thin text book or an ordinary sized novel or a dictionary or encyclopedia. The place mark 17 is furthermore adjustable with respect to the clasp so as to be capable of insertion between any 105 two leaves of the book. The downwardly extending finger is practically movable on an arc described about the vertical axis of the clasp 5, 6 while the D-ring 21 and large hole 20 permits a freedom of movement which 110

enables the finger to adjust itself parallel to the leaves at any point. As the place mark 17-22 is relatively stiff, the book will naturally fall open, when desired, at the place 5 where the place mark is inserted and there is thus no danger of tearing the leaves when the book is opened as would be the case where a ribbon or cord were used to mark the place.

Various modifications will occur to those 10 skilled in the art in the composition and configuration of the component elements going to make up the book mark as a whole and no limitation is intended by the illustration in the accompanying drawings or phraseology in the foregoing specification, except 15 as indicated in the appended claims.

What I claim is:—

1. A book mark comprising, in combination, a clasp adapted to grip the back binding of a book and formed with an elongated slot and a relatively inflexible place mark formed at one end with means to be received in and slide in the slot and at the opposite end with an angularly bent finger for insertion between any two leaves of a book.

2. In a book mark, a clasp comprising a flap formed with a downwardly extending tongue cut out therefrom, said flap being adapted to be inserted within the inside of 20 the back binding of a book with the tongue

outwardly of said binding, so as to grip the binding therebetween and said clasp being also formed above the tongue with an elongated slot defined in part by an arcuate side remote from the tongue, and a place mark 35 formed with a hole at one end to receive the arcuate side of the slot and slide with respect thereto, the opposite end of the arm being bent at an angle for insertion between any two leaves of a book.

3. In a book mark, a pliable but relatively inflexible clasp comprising a flap formed with a downwardly extending tongue cut out therefrom, said flap being adapted to be inserted within the inside of the back binding of a book with the tongue outwardly of said binding, so as to grip the binding therebetween and said clasp being also formed above the tongue with an elongated slot defined by a substantially rectilinear side proximate the tongue and an arcuate side remote from the tongue, and a pliable but relatively inflexible arm formed with a relatively large hole at one end to receive the arcuate side of the slot and slide freely thereon, the opposite end of the arm being bent at an angle to the remainder of the arm for insertion between the leaves of a book.

In testimony whereof I affix my signature.
JACOB M. DEUTSCH.
